UNITED STATES PATENT OFFICE.

WILLIAM M. SAUNDERS, OF WATERBURY, CONNECTICUT, ASSIGNOR TO THE HOGE MANUFACTURING COMPANY, OF NEW YORK, N. Y., A CORPORATION OF NEW YORK.

PROPEL PENCIL.

Application filed September 2, 1921. Serial No. 497,832.

To all whom it may concern:

Be it known that I, WILLIAM M. SAUNDERS, a citizen of the United States, residing at Waterbury, county of New Haven, State of Connecticut, have invented certain new and useful Improvements in Propel Pencils, of which the following is a full, clear, and exact description.

The present invention relates to propel pencils, and has for its object to provide a novel and improved pencil of this character which is simple, cheap and durable in construction, and reliable and efficient in operation.

The several features of the invention will be clearly understood from the following description and accompanying drawings, in which:

Figure 1 is a longitudinal sectional view, partly in elevation, of a pencil embodying the features in their preferred form;

Fig. 2 is a similar view on an enlarged scale of portions of the pencil;

Figs. 3, 4, 5 and 6 are sectional views taken on the lines 3—3, 4—4, 5—5 and 6—6 of Fig. 2, respectively;

Fig. 7 is a detail side elevation of a tubular casing for the pencil lead propeller; and

Fig. 8 is a detail side elevation of a portion of the lead propelling mechanism, with the parts separated.

The body of the pencil as illustrated in the drawings is provided with a cylindrical casing 2 and a tip 4, having a swivel connection between them to enable the casing and tip to be rotated relatively. The swivel connection comprises an elongated bushing 6 secured in the lower or forward end portion of the casing, the extreme forward end of the casing being turned inwardly to provide a flange 8 engaging the forward end of the bushing 6 to assist in securing the bushing in the casing. Spaced bushings 10 and 12 are secured in said bushing 6 with the bushing 10 spaced from the forward end thereof and with the rear end of the bushing 12 engaging an inwardly extending flange 14 formed on the rear end of the bushing 6. A nut 16 is arranged between the bushings 10 and 12 and is held from longitudinal movement by engagement with the opposite ends of the bushings, but is free to be rotated with relation to the bushings. The nut 16 is provided with a forwardly extending

sleeve bearing 18 which extends into and is secured to the rear portion of a bushing 20. This portion of the bushing 20 is reduced and arranged for rotation within the bushing 10 and the forward end of the sleeve 18 of the nut is turned outwardly to engage a shoulder 22 formed in the bushing 20 to assist in securing the bushing and nut together. The bushing 20 is provided with a shoulder 24 arranged adjacent the forward end of the bushing 10 and is provided with a peripheral portion 26 which forms a bearing for the portion of the bushing 6 extending between its forward end and the forward end of the bushing 10. The bushing 20 constitutes the tip member of the swivel connection and its forward end portion extends into and is secured to the rear end portion of the tip, the rear end of the tip being turned inwardly to provide a flange 28 that engages a shoulder formed on the bushing 20 to assist in securing the bushing and tip together. In order to take care of any looseness of parts of the swivel connection caused by wear and also to place a certain amount of frictional drag on the relatively movable parts of the swivel connection, a spring washer 30 is arranged on the rear reduced portion of the bushing 20 and is positioned between the rear end of the bushing 10 and the shoulder 24 on the bushing 20. From the foregoing it will be apparent that the parts of the swivel connection may be easily assembled, that they are of simple and durable construction and not liable to get out of order.

To guide the lead through the tip, a lead guiding tube 32 is provided, the forward end of which engages the forward end of the tapering wall of the tip and the rear end portion of which is secured in the sleeve 18 of the nut 16. The nut 16 is provided with an axial aperture through which a screw-threaded follower or pencil lead propelling screw 34 is screw threaded. The rear end of the propeller screw 34 is provided with a laterally extending tongue 36 which engages an elongated slot 38 in a tubular casing 40, the forward end of which is secured in the bushing 12. With this construction it will be apparent that by relatively rotating the casing 2 and the tip 4 of the pencil the propeller screw 34 may be advanced and retracted as desired.

In order that the propeller screw 34 shall not become disengaged from the nut by excessive relative rotation of the nut and screw, the forward end of the propeller screw is provided with a reduced portion 42 which will extend into the aperture of the nut in case the screw threaded portion of the propeller screw should be retracted from the nut. Also, in order to insure that the threads of the propeller screw and the nut may be properly engaged upon relative rotation of the casing 2 and the tip 4 by the user in case they should become disengaged by an excessive rotation of the nut and screw, a coiled spring 44 is arranged in the propeller screw casing 40 which acts as a yielding abutment for the propeller screw near the end of its retracting movement and when thus engaged tends to urge the propeller screw through the nut.

In the illustrated construction means is provided for preventing lead from being jammed back and forcing the end 42 of the propeller screw out of the nut when the propeller screw has been retracted so that the propeller screw could not be again effectively operated without first removing the excess of lead. This means comprises a detachable head 46 having a body portion in sliding engagement with the lead guiding tube 32 and having a rearwardly extending portion in the form of a split sleeve adapted to frictionally grip the reduced end portion 42 of the propeller. The head is also provided with a reduced forward end portion 48 for engagement with the lead. With this construction it will be apparent that it would be quite impossible to render the propeller screw inoperative by forcing the lead into the lead guiding tube. As the head 46 is frictionally secured to the propeller screw, it will by engagement with the nut co-operate with the coiled spring 44 to yieldingly limit the retracting movement of the propeller screw. By thus yieldingly limiting the retracting movement of the propeller screw, it will be apparent that there is no danger of parts of the pencil being injured by forceful turning of the casing 2 and tip 4 after the propeller screw has been retracted.

While it is preferred to employ the specific construction and arrangement of parts illustrated and described, it is to be understood that this construction and arrangement is not essential except so far as specified in the claims.

What I claim is:

1. A pencil of the class described having upper and lower relatively rotatable parts, the lower part comprising a screw-threaded nut portion rotating therewith, in combination with a screw-threaded follower engaging the thread of said nut and capable of being withdrawn from operative engage-

ment therewith, said follower being movable longitudinally relatively to said upper part and operatively connected thereto so as to rotate therewith, and a yielding abutment carried by said upper part and arranged to be compressed by said follower as it approaches its upward limit of movement and thereupon to urge said follower toward operative engagement with said nut.

2. A pencil of the class described having, in combination, a body, a tip, co-operating members constituting a swivel connection between the body and tip to enable the body and tip to be rotated relatively, a spring interposed between said co-operating members to compensate for any looseness of parts in said swivel connection, and a propeller arranged for advancing movement to feed the pencil lead through the tip on relative rotation of said body and tip in one direction.

3. In a propel pencil the combination of a casing comprising a body portion and a tip portion having their inner ends juxtaposed; a bushing fixed within one of said portions and adjacent to the inner end thereof, a follower carrier secured to said bushing, a second bushing, the same being located within the inner end of the other of said portions and having an extension entering the inner end of said first portion and free to turn therein, said extension having a reduced portion forming a shoulder spaced from its end and a lateral projection adjacent to its end, said shoulder and projection constituting abutments, a sleeve loosely mounted between said abutments and held fixed within the said inner end of said first portion, said extension having an internally threaded aperture at the end within said first portion, and a screw-threaded follower engaging the screw thread of said aperture and having a sliding engagement with said follower carrier.

4. In a propel pencil the combination of a casing comprising a body portion and a tip portion having their inner ends juxtaposed, a bushing fixed within one of said portions and adjacent to the inner end thereof, a follower carrier secured to said bushing, a second bushing, the same being located within the inner end of the other of said portions and having an extension entering the inner end of said first portion and free to turn therein, said extension having a reduced portion forming a shoulder spaced from its end and a lateral projection adjacent to its end, said shoulder and projection constituting abutments, a sleeve loosely mounted between said abutments and held fixed within the said inner end of said first portion, said extension having an internally threaded aperture at the end within said first portion, and a screw-threaded follower engaging the screw thread of said aperture.

ture and having a sliding engagement with said follower carrier, and a spring between said sleeve and one of said abutments.

5. In a prop pencil the combination of
a casing comprising a body portion and a tip portion having their inner ends juxtaposed, a bushing fixed within one of said portions and adjacent to the inner end thereof, a follower carrier secured to said
10 bushing, a second bushing, the same being located within the inner end of the other of said portions and having an extension entering the inner end of said first portion and free to turn therein, said extension having a reduced portion forming a shoulder spaced from its end and a lateral projection adjacent to its end, said shoulder and projection constituting abutments, a sleeve loosely mounted between said abutments and held fixed within the said inner end of said
20 first portion, said extension having an internally threaded aperture at the end within said first portion, and a screw-threaded follower engaging the screw thread of said aperture and having a sliding engagement with said follower carrier, and a third bushing within the inner end of said first portion and with which said first bushing and sleeve make binding engagement.

6. A pencil of the class described having, 30 in combination, a lead guide, a support therefor, a nut fixed relatively to said support, a follower having a screw-threaded portion adapted to make engagement with said nut and adapted by rotation to be projected into and withdrawn from said nut and guide, a member sliding within said guide and movable independently of said follower, said member acting to separate a lead within said guide from said propeller 40 and its nut, and means for rotating said propeller relatively to said nut so as to advance and retract the same.

7. A pencil of the class described having, 45 in combination, a casing comprising two relatively rotatable parts, a nut secured to one of said parts to rotate therewith and provided with a screw threaded axial aperture, a propeller connected with the other of said parts and screw threaded through 50 said axial aperture, a lead guiding tube into which the propeller is adapted to extend, and a member detachably secured to the forward end of the propeller, arranged to slide in said lead guiding tube and interposed between the forward end of the propeller and the lead. 55

WILLIAM M. SAUNDERS.
